UNITED STATES PATENT OFFICE.

FREDERICK L. WHITCOMB, OF CLYDE, OHIO.

CAN OPENER.

Application filed April 6, 1921. Serial No. 459,003.

To all whom it may concern:

Be it known that I, FREDERICK L. WHITCOMB, a citizen of the United States, residing at Clyde, in the county of Sandusky and State of Ohio, have invented certain new and useful Improvements in Can Openers, of which the following is a specification.

This invention relates to improvements in can-openers; and its leading purpose is to provide simplicity of construction coupled with efficiency of operation.

Thus the prime object of my present invention is to produce a highly efficient hand implement for opening tin cans, or the like, at the lowest possible cost of manufacture and distribution. It is also an important object of the invention to provide the most sanitary article of this character; that is to say, an article easily cleansed, having a minimum of re-entrant angles and recesses, and without interstices which catch and retain dirt and deleterious matter. Another object is to furnish a self-contained, integral structure having no screws, washers or other component parts which can become loosened or lost, or which may require adjustment. Further objects are to make the sharp steel fulcrum edges integral with the blade; to provide a blade which may be sharpened readily without removal, and which is well guarded to protect the user from injury; to produce an instrument of this class for use by both right and left-handed persons; and to design an opener to cut close to the edge of a can and turn outward the cut edge of the tin, so that the contents of the can may be easily removed therefrom intact.

Minor objects will become apparent from the following description of a preferred embodiment of my invention, reference being had to the accompanying drawing, in which—

Fig. 1 is a front view,

Fig. 2 is a side view, and

Fig. 3 is a view of the cutting end of the implement.

Fig. 4 shows the inside face of the steel blade member.

Fig. 5 is an outline of the sheet steel blank from which the blade member is formed.

The reference numeral 1 indicates the blade member of hard or alloy steel, preferably self-hardening steel, having cutting edges 2 on each side of it terminating in a sharp point 3, and provided with rounded

ears 4, one on each side oppositely disposed at the base of the blade and bent over at right angles to the flat sides of the latter. The blade member 1 is reduced in width at the junctures of the ears 4, and is prolonged as an anchoring tang 5 which resembles a dovetail, being broader at its terminal than at its root.

In fashioning the blade member 1 I first punch out a blank from sheet steel of the proper thickness, as outlined in Fig. 5. The ears 4 of the blank are then bent over sharply at right angles, and the cutting edges 2 beveled off by grinding or otherwise, as shown in Figs. 1 to 4.

The completed blade member 1 is placed in a mold, and a metal handle member 6 is cast in a melted condition about it, as shown in Figs. 1, 2 and 3. Any suitable metal may be employed for casting the handle member 6, but aluminum is preferred. The tang 5 is wholly embedded in the casting 6, which latter is bifurcated, having a space between its branches substantially corresponding to the breadth of the ears 4. The inner and shorter branch 7 has a beveled termination and serves as a brace and backing for the blade 1. The outer and longer branch 8 terminates somewhat beyond the blade point 3, and has its inner face parallel with the face of the blade, so that it may serve as a guide for the latter. The handle member 6 and its branches 7 and 8 are made flush with the outer faces of the ears 4, and the curved upper edges of the said ears project above the bottom of the groove between said branches. Thus the ears 4 are backed and braced by the metal of the casting 6, while their curved upper edges remain sharp cornered and exposed.

In operation the implement is first applied approximately vertically, the guide 8 being brought against the side of the can, and the point 3 of the blade bearing on the top thereof, whereupon pressure is exerted to force the point 3 and cutting edges 2 to pierce the can top. After the blade is inserted the handle 6 is swung downward, thereby causing the sharp outer corner of the rounded edge of one of the ears 4 to bite into the upper edge of the can and serve as a fixed fulcrum for the leverage of the handle while the latter is tilted further, which causes the blade to rise and its upper edge 2 to cut through the metal of the

can top, which cut may be continued if desired substantially throughout the length of the cutting edge. The opener is then advanced in the cut, and the operation repeated until the necessary opening is made in the can. The guide 8 and the rounded fulcrum edge 4 force the blade to cut smoothly, close to and parallel with the edge of the can, turning the cut edge outward, so that 10 the contents of the can may be removed with a minimum of injury and obstruction.

I further point out and distinctly claim as my invention:—

1. A can-opener comprising a cutting 15 blade member provided with fulcrum ears disposed at right angles thereto, and having a prolonged anchoring tang, said blade member being formed from a sheet steel blank; and a metal handle and an integral 20 terminal guide member cast in a molten state about the tang and ears of the blade member.

2. A can-opener comprising a cutting blade member provided with fulcrum ears

disposed at right angles thereto, and having 25 a prolonged anchoring tang; and a metal handle member provided with an integral terminal guide projecting therefrom parallel with and oppositely disposed to the blade member, said handle member being cast in a 30 molten state about the tang and ears of the blade member.

3. In a can-opener, a bifurcated handle member, the longer branch thereof forming a flat-faced guide, and the shorter branch thereof forming a blade brace, a cutting blade set against said brace and projecting parallel with said guide, a prolongation of 35 said blade forming an anchoring tang in said handle member, and a pair of fulcrum 40 ears carried by said blade disposed one on each side thereof at right angles thereto, said ears being partly embedded in said handle member at the bottom of the groove between the said branches thereof. 45

In testimony whereof I affix my signature.

FREDERICK L. WHITCOMB.
